UNITED STATES PATENT OFFICE

171,442

ORNAMENTAL CHAIN

Erwin W. Deines, Cranston, R. I., assignor to
Chain Craft Co., a corporation of Rhode Island

Application July 3, 1952, Serial No. 20,457

Term of patent 3½ years

(Cl. D45—16)

To all whom it may concern:

Be it known, that I, Erwin W. Deines, a citizen of the United States of America, residing at Cranston, county of Providence, State of Rhode Island, have invented a new, original, and ornamental Design for an Ornamental Chain, of which the following is a specification, reference being had to the accompanying drawing forming a part thereof.

Fig. 1 is a side elevational view of an ornamental chain, showing my new design;

Fig. 2 is a view of the chain shown in Fig. 1 rotated in an angle of 90°;

Fig. 3 is a view of the opposite side of the chain as shown in Fig. 1;

Fig. 4 is a sectional view through one end of a link, taken substantially along line 4—4 of Fig. 2; and

Fig. 5 is a sectional view through another link taken along line 5—5 of Fig. 2.

I claim:

The ornamental design for an ornamental chain, substantially as shown.

ERWIN W. DEINES.
